[57] **CLAIM**

The ornamental design for a hanger holder, as shown
and described.

DESCRIPTION

FIG. 1 is an isometric view of a hanger holder embodying
my new design;

FIG. 2 is a front view of the hanger holder shown in
FIG. 1;

FIG. 3 is a rear view of the hanger holder shown in
FIG. 1;

FIG. 4 is a top view of the hanger holder shown in FIG.
1;

FIG. 5 is a bottom view of the hanger holder shown in
FIG. 1; and,

FIG. 6 is a left-hand view of the hanger holder shown
in FIG. 1, a mirror image of the right-hand view
thereof.

FIG. 1

FIG. 3

FIG. 2

FIG. 4

FIG. 6

FIG. 5
